UNITED STATES PATENT OFFICE.

JULIUS SUES, OF LOUISVILLE, KENTUCKY.

DESIGN FOR ORNAMENTING THE REAR OF A CHILD'S CARRIAGE.

Specification forming part of Design No. 7,847, dated November 3, 1874; application filed September 5, 1874.
[Term of Patent 7 years.]

To all whom it may concern:

Be it known that I, JULIUS SUES, of Louisville, Jefferson county, Kentucky, have invented a Design for Child's Carriage, of which the following is a specification:

The nature of my design is fully set forth in the accompanying photographic illustration, to which reference is made.

A represents the body of a child's carriage, to which are applied, at the rear or other part thereof, by suitable fastening devices, plain or gilt metallic chains B, which are hung to connect with the rear springs in some suitable manner, and looped by a buckle or clasp, α , of ornamental shape, so that a neat and rich ap-

pearance to the carriage is obtained. They are mainly intended to take the place of the unsightly leather straps hitherto employed for trimming up such carriages, and which I do not claim.

I claim as my invention—

The design for the ornamentation or trimming of the rear of a child's carriage, consisting essentially of the crossed chains B and buckle α , substantially as represented.

JULIUS SUES.
